BY His ATTORNEY.

UNITED STATES PATENT OFFICE.

HENRY PRICE BALL, OF PITTSFIELD, MASSACHUSETTS, ASSIGNOR TO GENERAL ELECTRIC COMPANY, A CORPORATION OF NEW YORK.

ELECTRIC HEATER.

1,021,230.

Specification of Letters Patent. Patented Mar. 26, 1912.

Application filed February 16, 1910. Serial No. 544,238.

To all whom it may concern:

Be it known that I, HENRY P. BALL, a citizen of the United States, residing at Pittsfield, in the county of Berkshire, State 5 of Massachusetts, have invented certain new and useful Improvements in Electric Heaters, of which the following is a specification.

This invention relates to electric heaters and the like and has for its object the 10 provision of a device of this character in which the heating element or resistance conductor is held in intimate thermal relation with the body to be heated in a simple and efficient manner.

15 One of the objects of my invention is to provide an electric heater in which the resistance conductor is held in contact with the metallic body to be heated by integral portions of the body itself, so as to approach 20 as closely as possible the actual embedding of the conductor in the iron.

In carrying out my invention I form depressions or grooves in the metallic body to be heated and place the conductor in the 25 grooves. The sides of the grooves extend above the conductor and can be bent down over the conductor to practically inclose it, and an excellent conducting condition between the conductor and the body is effected.

30 In the accompanying drawing, in which I have shown my invention embodied in concrete form for purposes of illustration, Figure 1 is a plan view of the heating element; Fig. 2 is a sectional view of the same mounted so as to form a stove; and Figs. 3, 4 and 35 5 are detail views showing the means for securing the conductor in place.

Referring to the drawings, 10 represents the metallic body to be heated. I have 40 shown it in the form of a flat disk which is adapted to form a stove. The under side of the plate is grooved, as shown, in the form of a spiral groove 11, although it is obvious that any other suitable form of 45 grooving may be employed. This plate may have the grooves formed therein in various ways; for instance, the grooves may be drop-forged into the disk or the plate may be in the form of a malleable casting. The 50 sides 12 of the grooves extend above the surface of the plate and are tapered, as shown. The resistance conductor 13 is then placed in the groove and insulated therefrom. This insulation may be produced by 55 winding asbestos or other insulating ma-

terial around the wire, or by folding a piece of mica around the wire as shown in Fig. 5, and placing it in the groove. When the conductor is laid in the groove and insulated from the metal, the edges of the groove 12 are bent down over the conductor. This may be done in any desired manner, as, for instance, by passing it through suitable rolls. The edges are pressed tightly upon the conductor, so as to hold the latter under pressure and force it into intimate thermal relation with the plate. Heat is thus conducted away from the wire to the working surface in a very efficient manner, since a large portion of the conductor is in contact with the metal. The plate is then mounted in a frame, as shown, and the leads brought down to the terminal pins 15.

I have shown and described my invention for purposes of illustration as being constructed in a specific manner, but it is obvious that my invention is not limited either to the particular form of heater or to the construction and arrangement of parts herein shown and described, since various 80 modifications will suggest themselves to those skilled in the art without departing from the spirit of my invention, the scope of which is set forth in the annexed claims.

What I claim as new and desire to secure 85 by Letters Patent of the United States, is:—

1. The process of making electric heaters, which consists in forming a groove in a metallic body to be heated, placing a resistance conductor in said groove, and bending the metal forming the side of the groove over the conductor to hold it securely in place.

2. The process of making electric heaters, which consists in forming a spiral groove in 95 a metallic body to be heated, placing a resistance conductor in said groove and bending the metal forming the side of the groove over the conductor to hold it in place.

3. The process of making electric heaters, which consists in grooving a metallic plate throughout one of its surfaces, placing a resistance conductor in the grooving and bending the metal over the conductor to hold it in place.

4. An electric heater comprising a grooved metallic body and a resistance conductor in said groove and insulated therefrom, the metal forming the groove being bent over the conductor.

5. An electric heater comprising a plate grooved on one side and a resistance conductor in said grooves and insulated therefrom, the metal forming one side of the groove being bent over the conductor.
6. An electric heater comprising a plate having a spiral groove in one side thereof, a resistance conductor in said groove and

insulated therefrom, the metal forming the groove being bent over the conductor. 10

In witness whereof, I have hereunto set my hand this 3rd day of Feb., 1910.

HENRY PRICE BALL.
